225,097

PHONOGRAPH RECORD HOLDER

Julian Gutierrez, 6233 Brookview Ave.,
Minneapolis, Minn. 55424

Filed Mar. 17, 1971, Ser. No. 125,445

Term of patent 14 years

Int. Cl. D6—99

U.S. Cl. D6—185

FIG. 1

FIG. 2

Des 225,097

PAGE 2

FIG. 3

FIG. 4

FIG. 5

FIG. 6

FIG. 1 is a perspective view of a phonograph record holder showing my new design;

FIG. 2 is a view in side elevation on a reduced scale;

FIG. 3 is a view partially in horizontal section taken on line 3—3 of FIG. 2;

FIG. 4 is a view in front elevation on a reduced scale;

FIG. 5 is a bottom plan view; and

FIG. 6 is a view in rear elevation on a reduced scale.

I claim:

The ornamental design for a phonograph record holder, as shown.
